(57) **CLAIM**

The ornamental design for an analysis chip for biochemical testing machine, as shown and described.

DESCRIPTION

FIG. 1 is a front view of an analysis chip for biochemical testing machine showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof; and,

FIG. 8 is a rear perspective view thereof.

The broken lines, the areas within the broken lines, and the areas bounded by the broken lines and solid lines depict portions of the analysis chip for biochemical testing machine that form no part of the claimed design.
